CLAIM

The ornamental design for a unitary wire stake, as shown and described herein.

DESCRIPTION

FIG. 1. Is a left side elevational view of our unitary wire stake with the right side elevational view being a mirror image thereof;

FIG. 2. Is a top plan view thereof;

FIG. 3. Is a bottom plan view thereof;

FIG. 4. Is a front elevational view thereof;

FIG. 5. Is a rear elevational view thereof;

FIG. 6. Is a left side elevational view of an alternate embodiment of our unitary wire stake with the right side elevational view being a mirror image thereof and with the dotted line showing being for illustrative purposes only and for which no claim is made;

FIG. 7. Is a top plan of the FIG. 6 embodiment with the dotted line showing being for illustrative purposes only and for which no claim is made;

FIG. 8. Is a bottom plan view of the FIG. 6 embodiment with the dotted line showing being for illustrative purposes only and for which no claim is made;

FIG. 9. Is a front elevational view of the FIG. 6 embodiment with the dotted line showing being for illustrative purposes only and for which no claim is made; and,

FIG. 10. Is a rear elevational view of the FIG. 6 embodiment with the dotted line showing being for illustrative purposes only and for which no claim is made.
